HIGHWAY GUARD RAIL

John E. Opgenorth, Nashotah, Wis.

Application March 17, 1939, Serial No. 262,467

8 Claims. (Cl. 256—13.1)

My invention relates to highway guard rails.

The object of my invention is to provide an improved highway guard rail construction and support and anchorage therefor, whereby even along a curved highway line to provide elements of resiliency and flexibility and at the same time superlative strength.

Another object of my invention is to provide a new type of highway guard rail support which, although anchored, is capable of substantial lateral or swivelling skid-like motion.

In the drawings:

Fig. 1 is a side elevation of a highway guard rail construction embodying my invention, portion of the support and anchorage being shown in vertical section.

Fig. 2 is a plan view of the construction shown in Fig. 1.

Fig. 3 is a side elevation in enlarged detail of one of my guard rail supports.

Fig. 4 is a plan view of the device shown in Fig. 3.

Fig. 5 is a section on line 5—5 of Fig. 3.

Like parts are identified by the same reference characters throughout the several views.

My highway guard rail supporting and anchoring structure includes supporting units 10 comprising multi-legged supports spaced apart for the holding and supporting of guard rails or cables 11—12, each of the supporting units having skid-like shoes 13 at the lower ends of their respective legs, said shoes being adapted to bear upon either a concrete slab 14 or upon the earth constituting the highway "shoulder" 15.

In the drawings, I have shown my supporting units 10 shaped in the form of a tripod having a forward leg 16 and two rearward legs 17 and 18 made of a conventional channel. The forward leg 16 is placed nearest to the highway road surface and is preferably substantially vertical. The rear legs 17 and 18 are somewhat inclined and braced with reference to the forward leg 16 by upper brace member 19 and lower brace member 20. Additional brace members 21 may be provided to give adequate strength.

Clamps 22 and 23, which may be in the shape of U-bolts as shown in Figs. 4 and 5, are used to clamp cables 11 and 12 relatively tightly to the supporting unit.

Below each of the supporting units 10, I anchor a flexible cable 25 which extends substantially vertically upwardly adjacent a clamp strut 26 extended across the lower brace 20, this clamp strut being of heavy material and provided with a clamp 260 through which the anchor cable extends. Above the strut 26, I provide an anchor cable clamp 27 to frictionally engage the anchor cable 25. The anchor cable extends through this clamp a distance of 8 or 10 inches to a stop terminal 28 which comprises a leaded or otherwise

permanently affixed head for the end of the anchor cable. Each of the clamps is provided with clamp bolt 29 and may be drawn relatively tightly so as to frictionally engage the anchor cable 25.

At any convenient point, but preferably adjacent the top of my supporting unit 10, I mount a signal 50 which may carry reflective material to indicate its position at night under the lights of approaching vehicles. This signal is mounted upon a bracket 51 for movement to and from position shown in full lines in Fig. 5. The standard 52 upon which the signal is mounted is crank-like in its configuration and provides a horizontally extended arm or lever 53. This lever is connected by means of a spring 54 to the head 28 of the anchor cable 25. If my supporting unit is displaced from its intended position, the anchor cable will be drawn down through the clamps as described above and, when so drawn down, will cause the signal 50 to assume the position shown in dotted lines at 55, this indicating to a highway maintenance engineer that the supporting unit has been moved from its intended position. Since the cable when pulled downwardly through the clamp 260 will not be returned to its original position until the engineer has released the clamp and replaced the supporting unit to its intended position, the signal will remain in the dotted line position until the engineer replaces it in its erect position.

At the end of the line of cable 11—12, I provide the usual "dead man" 30 and dead man cable 31. The cable 31 extends over a snubbing post 32 and at the end of the cable 31 I provide a turnbuckle 33 which, in turn, is secured to a wedge block 34 about which the cable 11—12 is laced by tightening the turnbuckle 33. The wedge block 34 draws the cables 11—12 tightly through the U-bolts or clamps 22—23.

As indicated above, I prefer to mount my supporting units 10 upon concrete slabs 14. In any event, I provide a slab 35 for the end support 10 and I incline the surface of the slab 35, as shown in Fig. 1, so that if the support 10 is struck by a vehicle and moved longitudinally of the cable 11—12, a tightening action with respect to the cable 11—12 will result.

From the above description, it will be seen that each of my multi-legged supporting units 10 is individually frictionally anchored to its cable 25 by means of clamp 260, but each of the units being mounted upon skid shoes 13 is purposely adapted to skid or slide under the impact of a vehicle which may strike the cable 11—12 or may strike one of the supporting units 10 directly. If the weight or impact of a vehicle against one of the cables 11 or 12 or against one of my supporting units 10 is such as to require that the supporting unit move despite the frictional engagement of the clamp 260 upon the cable 25, the

cable will be drawn through the clamp until the clamp 27 contacts the clamp 260, whereupon an augmented total friction including the frictional engagement of the cable through the clamp 260 plus the resistance of the movement of the cable through the clamp 27 will be available to counteract the forces attempting to move my supporting unit. If the movement continues, however, the ultimate contact of the stop terminal 28 against clamp 27 will determine the final movement of the supporting unit. Beyond this, my unit may not move without destruction of the unit, the breakage of cables 11 or 12, or rupture of the anchor cable 25. If the unit 10 has been displaced laterally sufficiently to bring the stop terminal 28 in contact with the clamp 27, the cable 25 in passing through the anchor plate 26 will be "snubbed" about the plate so as to give the terminal 28 and the clamp 27 a considerable "advantage." In practical use and test of my highway guard rail supports, I have found that it is virtually impossible to displace one of my supporting elements 10 beyond the ultimate limit of movement determined by the contact of the terminal 28 with the clamp 27.

Obviously with the construction such as that described above, it is possible not only to move my guard rail support rearwardly away from the highway, but it is also possible to move the support along the cable 11-12 and I thus provide a flexibility and resiliency of guard rail cable support that is far superior to any support such as the ordinary fence posts or metal supporting posts which are mounted upon springlike anchorage members. My entire tripod or multi-legged supporting element may skid or slide relatively freely within limits and the resulting damage to the guard rail supports and to any vehicle which may be brought in contact with my device is exceedingly small.

In actual use, I have found that my supporting unit is particularly free for movement which might be termed a swivelling movement which results from the glancing impact of a vehicle or other object using the highway, since the contact of such vehicle or object against the clamps 22 or 23 may move my supporting unit in the skid-like motion along the cable or rail 11-12. At the same time, my unit rotates about the anchor cable 25 and releases the clamps 22 and 23 from engagement with any portion of the vehicle.

I claim:

1. A highway guard rail construction including individual multi-legged supporting units each capable of skid-like movement in upright position, and a flexible cable-like anchor member substantially vertically disposed between the legs of each unit and clampingly secured relatively thereto the clamping engagement being provided by means including a multiple of clamping members spaced apart whereby in the continued skid-like movement of the supporting unit to provide increasing resistance to said movement.

2. A highway guard rail support and anchor therefor including a multi-legged supporting unit capable of skid-like movement in upright position and braces between said legs, a substantially vertically disposed anchor cable and a clamp connected to a brace and to said cable whereby in the skidding movement of the unit to displace 70 said cable in said clamp.

3. A highway guard rail support and anchor therefor including a multi-legged supporting unit capable of skid-like movement in upright position and braces between said legs, a substantially vertically disposed anchor cable and a clamp connected to a brace and to said cable whereby in the skidding movement of the unit to displace said cable in said clamp, said cable having a terminal member in position to strike the clamp in extreme movement of the unit and thereby limit said movement.

4. A highway guard rail supporting unit provided with a forward leg and divergent brace legs, said unit being capable of skid-like movement in upright position, highway rail supporting means adjacent the forward leg and an anchor cable between the forward legs and the brace legs.

5. A highway guard rail supporting unit mounted for skid-like movement with reference to an anchorage member, a signal for said unit, an anchorage member, and a connection between the anchorage member and the signal whereby to change the position of the signal when the unit has been displaced with reference to the position of the anchorage member and means for holding the signal in displaced position against automatic return even though the unit has been returned to its original position.

6. A highway guard rail and support therefor including in said support anchorage means extending from the highway shoulder upon which said support is rested, a clamp forming part of said support and frictionally engaging said anchorage means, a second clamp upon said anchorage means spaced from said first clamp, and a stop terminal upon the anchorage means spaced from said second clamp whereby in the displacement of said supporting means to provide increasing resistance to movement of the support upon the shoulder.

7. A highway guard comprising an upright unit having a base portion by which the unit is supported for skid-like movement in upright position, and an upright flexible cable-like member having connections at its end portions between said unit and the surface on which said unit is supported whereby said unit is normally held in fixed position on said surface, one of said connections being constituted by readily accessible clamping means in which said member is slidably so that said unit under impact is bodily movable subject to the frictional resistance afforded by the clamp connection.

8. A highway guard comprising an upright unit having a base portion by which the unit is supported for skid-like movement in upright position, an upright flexible cable-like member having connections at its end portions between said unit and the surface on which said unit is supported whereby said unit is normally held in fixed position on said surface, one of said connections being constituted by a readily accessible clamping means in which said member is slidable so that said unit under impact is bodily movable subject to the frictional resistance afforded by the clamp connection, and a fixed stop on the extremity of the clamped portion of said member adapted to engage said clamping means and thereby positively limiting movement of said unit.

JOHN E. OPGENORTH.
